UNITED STATES PATENT OFFICE.

ALBERT K. SMITH, OF WEST ORANGE, NEW JERSEY, ASSIGNOR TO WIREBOUNDS PATENTS COMPANY, A CORPORATION OF MAINE.

MACHINE FOR USE IN MAKING BOXES.

Application filed November 9, 1923. Serial No. 673,723.

My invention relates to machines for use in making boxes, crates, box or crate blanks and parts thereof, and particularly to machines for making wirebound box or crate blanks and parts thereof.

Among other objects, my invention is intended to provide a machine of the class described with improved means for controllably locating the fasteners which are driven into the box or crate parts to secure them together, and, when wirebound boxes or crates are desired, to secure binding wire thereto.

In the drawings:

Fig. 1 is a side elevation of a wirebound box blank machine embodying the invention, certain parts being broken away for clearness of illustration.

Fig. 2 is a top plan view of the machine, certain parts being left out for clearness of illustration.

Fig. 3 is an end elevation, partly in section, of a portion of the machine viewed from a point immediately in front of the stapling mechanism.

Fig. 4 is a side elevation, partly in section, seen from the line A—A of Fig. 2.

Figs. 5, 6 and 7 are enlarged detail views of a portion of the fastener-controlling mechanism; Fig. 5 being a top plan view, Fig. 6 a side elevation and Fig. 7 an end elevation.

Fig. 8 is a top plan view of a portion of one of the work-conveying chains showing materials for a box blank positioned thereon. Said figure also shows the pattern of staple-controlling blocks for a box blank extended in a straight line adjacent the box blank. It will be understood that in the machine the pattern of staple-controlling blocks are carried by an endless chain and do not extend in a straight line adjacent the blank.

Fig. 9 is a side elevation of the same.

Fig. 10 is the same as Fig. 8 except that the pattern of staple-controlling blocks is set for one-half a box blank only. This figure is inserted to illustrate how a pattern of staple-controlling blocks for one-half a box blank may be utilized to control the loca-

tions of staples in a succession of box blanks, the pattern repeating its operation on each succeeding half blank.

Fig. 11 is a side elevation of the same.

The machine selected for illustration is of the type disclosed in the copending application of Osceola C. Thompson, Serial No. 467,105 filed May 5, 1921, in which the box or crate parts are assembled on endless conveyer chains and are fed continuously at approximately a uniform speed past staple-forming and driving mechanism which is caused to operate at selected times to drive staples into the moving work, the staples being driven astride of binding wire to secure the same to the box parts.

In the machine of said Thompson application, the number and location of the staples is controlled by a series of blocks carried by an endless chain equal in length to the work-forwarding chains and travelling synchronously therewith; a staple-controlling block being set for each row of staples to be driven during one complete cycle of the work-forwarding chains. The work-forwarding chains being many times longer than the length of a box blank, it will be seen that a large number of staple-controlling blocks must be set (usually blocks for four or five blanks). The setting of so many blocks for each new run of box blanks is a long and laborious task. My invention is intended to reduce to a minimum the number of staple-controlling blocks which must be set, thereby reducing the time required to set up the machine for each new run of box blanks. I accomplish this result by providing mechanism whereby a pattern of controlling members for a single unit of work (a box blank or one-half of a box blank) will repeat its operation on a succession of units of work locating fasteners in each unit in accordance with the pattern.

The illustrative machine is designed to position in foldable relationship and feed sections of cleats *a* and side sheets *b* past staple-forming and driving mechanism, which forms staples from staple stock wire

automatically fed thereto and drives the staples over the binding wire *w* through the side sheets *b* and into or through the cleats *a*.

5 The cleats *a* and side sheets *b* are positioned by spacer blocks 1 carried by conveyer chains 2, which chains 2 travel on supports 3 and are trained over driven sprocket wheels 4 fast on a shaft 5 journalled in side frames 6 at the delivery end of the machine, and over idler sprocket wheels 7 on a shaft 8 journalled in side frames 6 at the receiving end of the machine. Conveyer chains 2 are usually of sufficient length to carry 10 spacer blocks for several blanks (for instance four or five) with spaces between blanks to provide the necessary wire extensions at either end of each blank to be twisted together to close the box when the blank is folded into box form.

Conveyer chains 2 are advanced continuously at approximately a uniform speed by power communicated from a hub 9 of a drive pulley 10 revolvably mounted on a stapler shaft 11 through a sprocket wheel 12 fast on hub 9, a sprocket chain 13, a sprocket wheel 14 on a stud shaft 15, and reduction spur gears 16, 17, 18, 19, 20 and 21, the latter being fast on shaft 5, all as fully shown 25 and described in said copending application of Osceola C. Thompson hereinabove referred to.

30 Staple-forming and driving mechanisms 22 are carried by a carriage 23 which is moved with the work while staples are being driven and is then returned to initial position. Carriage 23 is reciprocated over the work by bell-crank levers 24 and eccentrics 25 on stapler shaft 11, all as fully disclosed 35 in said application of Osceola C. Thompson hereinabove referred to. The staple-forming and driving mechanisms 22 are operated by pitman 26 from eccentrics 27 on stapler shaft 11. The arrangement is such that each time stapler shaft 11 is given one revolution carriage 23 will move with the work a certain distance during which time the staple-driving mechanisms will drive a row of 40 staples into the work and then the carriage will return to initial position.

45 Stapler shaft 11 is caused to revolve by clutching said shaft to the hub 9 of drive pulley 10. A suitable clutching mechanism for this purpose is shown and described in detail in said application of Osceola C. Thompson hereinabove referred to, reference to which is hereby made for a detailed description. It is sufficient here to say that when a buffer arm 28 (referred to in said 50 Thompson application as a "stop member 54") fast on a rock shaft 29 is raised out of contact with a clutch-controlling block 30 (referred to in said Thompson application as a "block 56"), stapler shaft 11 will be 55 clutched to hub 9 of drive pulley 10, and

when buffer arm 28 is again lowered into contact with clutch-controlling block 30, the clutch connection will be broken.

Rock shaft 29 is rocked at selected times to raise buffer arm 28 and cause a stapling 70 operation by a series of staple-controlling blocks 31 adjustably secured to a link chain 32 and each adapted in turn to engage and lower the upper end of a bell-crank lever 33 pivoted at 34 to a bracket 35, thereby rocking rock shaft 29 through a lever 36 fast on said shaft and having a pin and slot connection with bell-crank lever 33. A spring 81 returns bell-crank lever 33 and shaft 29 to initial position after a block 31 has passed 80 the upper end of said lever.

Chain 32 travels on a support 37 and is trained over an idler sprocket wheel 38 on a shaft 39 supported by a bracket 40 suspended from a bar 41 and over a driven 85 sprocket wheel 42 mounted on a shaft 44 supported by brackets 45. Chain 32 may be lengthened or shortened by the insertion or removal of links, bracket 40 being shiftable along bar 41.

90 As shown in Fig. 8, staple-controlling blocks 31 corresponding in number to the number of rows of staples to be driven into a box blank are secured to chain 32 at points corresponding to points on the box blank 95 where staples are desired, thus providing a pattern of variably spaced controlling members to control the number and location of staples in a box blank. It will be seen that, if said pattern is properly related to each 100 succeeding box blank on conveyer chains 2 and if chain 32 is then moved synchronously with conveyer chains 2, staples will be driven into each box blank in accordance with the number and location of said blocks 31. 105 Mechanism is, therefore, provided, first, to cause chain 32 to move with chains 2 and at the same rate of speed each time the leading spacer block 1 of a box blank is in proper alignment with the first staple-controlling 110 block 31; second, after the last staple has been driven into a blank, to cause chain 32 to move at a comparatively high rate of speed to bring the first staple-controlling 115 block 31 of the pattern up to proper position to move with the leading spacer block 1 of the next blank when said spacer block approaches the stapling plane; and, third, to cause chain 32 to remain stationary until the first spacer block 1 of the succeeding 120 blank is in proper alignment with the first staple-controlling block 31 of the pattern.

125 Chain 32 is moved synchronously with chains 2 by clutching sprocket wheel 42 to a sprocket wheel 46 revolvably mounted on shaft 44 and revolved constantly by a sprocket chain 47 from a sprocket wheel 48 fast on shaft 5, the size of the sprocket wheels 46 and 48 being such that chains 2 and chain 32 130 will move at the same rate of speed.

- Chain 32 is moved at a higher rate of speed by releasing the clutching engagement between sprocket wheel 42 and sprocket wheel 46 and clutching sprocket wheel 42 to 5 a sprocket wheel 49 revolvably mounted on shaft 44 and revolved constantly by a sprocket chain 50 from a sprocket wheel 51 fast on shaft 5, the size of sprocket wheels 49 and 51 being such as to cause chain 32 to move faster than chains 2.
- Chain 32 is stopped by disengaging sprocket wheel 42 from both sprocket wheel 46 and sprocket wheel 49.
- The clutch mechanism between sprocket wheel 42 and sprocket wheels 46 and 49 is best shown in Fig. 2 and consists of clutch pins 52 and 53 fast on a collar 54 and slidable on keys 43 on shaft 44; said pins 52 and 53 when shifted toward sprocket wheel 46 being adapted to enter openings 55 in the hub of sprocket wheel 46 and when shifted toward sprocket wheel 49 to enter openings 56 in the hub of sprocket wheel 49. The arrangement is such that the pins 52 and 53 may be stopped in a neutral position between sprocket wheels 46 and 49 and out of engagement with both.
- The mechanism for shifting collar 54 and clutch pins 52 and 53 consists of a rock shaft 57 carrying upright arms 58 having rollers 59 extending into a guideway 60 formed on the outer surface of collar 54 and adapted to shift collar 54 in the direction in which the rock shaft 57 is rocked. For instance, viewing Figs. 2 and 3, if rock shaft 57 is rocked in a clockwise direction, collar 54 and pins 52 and 53 will be shifted toward sprocket wheel 49 and when pins 52 and 53 enter the openings 56 in the hub 30 of sprocket wheel 49, chain 32 will be moved at a high rate of speed while if rock shaft 57 is rocked in a counterclockwise direction, collar 54 and pins 52 and 53 will be shifted toward sprocket wheel 46 and when pins 52 and 53 enter the openings 55 in the hub of sprocket wheel 46 chain 32 will be driven at the same rate of speed as chains 2. If rock shaft 57 is stopped with arms 58 in a vertical position, pins 52 and 53 will not be in engagement with either openings 55 in sprocket wheel 46 or openings 56 in sprocket wheel 49 and chain 32 will remain stationary.
- Rock shaft 57 is rocked by an arm 61 fast on rock shaft 57 and yieldingly held in its farthermost position to the right (viewing Fig. 7) by a spring 62 connecting arm 61 with a bracket 63 bolted to the crossbar of the machine. When arm 61 is in its farthermost position to the right (viewing Fig. 7), pins 52 and 53 are in engagement with openings 56 in the hub of sprocket wheel 49 and chain 32 travels at a higher rate of speed than conveyer chains 2. When arm 61 is moved to the left (viewing Fig. 7), in the manner hereinafter explained, pins 52 and 53 are withdrawn from openings 56 in the hub of sprocket wheel 49 and chain 32 will stop. When arm 61 is moved to its farthermost position to the left (viewing Fig. 7), pins 52 and 53 enter openings 55 in the hub of sprocket wheel 46 and chain 32 will move at the same rate of speed as conveyer chains 2.
- Arm 61 is moved to the left (viewing Fig. 7) a sufficient distance to release pins 52 and 53 from their engagement with openings 56 in the hub of sprocket wheel 49 by a pin 64 carried by the first staple-controlling block 31 of the pattern, which pin engages and moves one end of bell-crank lever 65 pivoted on bracket 63 and having a pin and slot connection 66 with a link 67 connected at one end to arm 61 and at its other end to a stop arm 68 pivoted on a bracket 69 bolted to the crossbar of the machine. When pin 64 moves the end of bell-crank lever 65 to the right (viewing Fig. 5), the other end of said lever acting through link 67 will move arm 61, thus rocking shaft 57 to neutral position. The connection between link 67 and stop arm 68 is of the pin and slot type and is so arranged that link 67 may be moved by bell-crank lever 65 without moving stop arm 68, so that stop arm 68 will be in position to engage pin 64 on the first staple-controlling block 31 as soon as said pin has moved the end of bell-crank lever 65 to the position shown in Fig. 5. Bell-crank lever 65 is held in this position by the pin 64, which pin is engaged and held stationary by the stop arm 68. Thus it will be seen that when pin 64 engages and moves the end of bell-crank lever 65, arm 61 and shaft 57 will be moved to neutral position and chain 32 will be stopped with the first staple-controlling block 31 of the pattern in correct position to move with the next box blank when it is brought forward by conveyer chains 2.
- Arm 61 is moved from neutral position to the left (viewing Fig. 7) to cause chain 32 to move synchronously with conveyer chains 2 by a pin 70 carried by the leading spacer block 1 for each box blank, which pin 70 engages and moves one end of a bell-crank lever 71 pivoted to a bracket 75, bolted to a crossbar of the machine. The other end of said lever is pivotally secured to arm 61. As best shown in Fig. 5, when pin 70 moves bell-crank lever 71, arm 61 and shaft 57 will be rocked to move pins 52 and 53 into engagement with openings 55 in the hub of sprocket wheel 46, and at the same time stop arm 68 will be raised through link 67, whereupon chain 32 will be moved synchronously with conveyer chains 2. To hold pins 52 and 53 in engagement with openings 55 in the hub of sprocket wheel 46, after pin 70 has passed bell-crank lever 71, a pawl 72 is provided to engage an extension 73 of

arm 61 when said arm has been rocked past the pawl 72 by bell-crank lever 71. Pawl 72, as best shown in Fig. 5, is pivoted to bracket 63 and is forced into engagement with extension 73 by a spring 74 attached to pawl 72 and the bracket 75. When pawl 72 has been swung into engagement with extension 73, chain 32 will move synchronously with conveyer chains 2 until pawl 72 is released from its engagement with extension 73.

Pawl 72 is released from its engagement with extension 73 of arm 61 by a pin 76 carried by the last staple-controlling block 31 of the pattern, which pin 76 engages and moves pawl 72 out of engagement with extension 73 of arm 61, thus permitting spring 62 to rock arm 61 and shaft 57 until pins 52 and 53 enter the openings 56 in the hub of sprocket wheel 49. In order that the last staple-controlling block 31 may engage and operate lever 33 before pin 76 engages pawl 72, said pin 76 is carried by a rearward extension 78 of said block. The rocking of arm 61 to the right (viewing Fig. 7) throws bell-crank lever 65 and stop arm 68 into the path of travel of pin 64 on the first staple-controlling block 31. Movement of stop arm 68 toward chain 32 is limited by a stop pin 77 secured to bracket 69.

Drive pulley 10 may be driven from a line shaft by a belt, not shown. An idler pulley 80 is provided to which the belt may be shifted to stop the machine.

The operation of the machine is as follows:

After threading the binding wires and staple stock wires in the usual and well known manner, the operator sets spacer blocks 1 on conveyer chains 2 the proper distances apart to position the several box blank sections with tie wire spaces between adjacent blanks; the leading spacer block 1 for each blank having a pin 70. He then determines the desired number and location of staples in a box blank and sets staple-controlling blocks 31 on chain 32 to correspond, that is, the number and spacing of blocks 31 will correspond to the desired number and spacing of staples in a box blank. The leading block 31 will be provided with a pin 64 and the last block 31 will be provided with a pin 76. The chain 32 should be adjusted (by the removal or insertion of links) to a length which is slightly longer than the length of a box blank so that the distance between the first and last blocks 31 will not be excessive. The first staple-controlling block 31 is preferably located directly in front of bell-crank lever 65 so that when the machine is started pin 64 will move bell-crank lever 65 and stop the pattern of blocks 31 in proper position to move with the first blank which passes beneath the staplers. Materials for the first blank are

then positioned on chains 2 and the machine is started by shifting the drive belt from idler pulley 80 to drive pulley 10. When the machine is started, pins 52 and 53 will be in engagement with openings 56 in the hub of sprocket wheel 49 and chain 32 will move pin 64 on the first staple-controlling block 31 quickly forward until it engages and moves bell-crank lever 65 and comes to rest against stop arm 68. At the same time, conveyer chains 2 will be moving the first box blank with its leading spacer block 1 toward the staplers. When pin 70 on the first spacer block 1 strikes bell-crank lever 71, stop arm 68 will be disengaged from pin 64, arm 61 and shaft 57 will be rocked throwing pins 52 and 53 into engagement with openings 55 in the hub of sprocket wheel 46 and chain 32 will move synchronously with conveyer chains 2, the pawl 72 holding arm 61 in the position into which it was rocked by bell-crank lever 71. As the pattern of blocks 31 move forward with the blank, each block in turn will strike and lower the upper end of bell-crank lever 33 thus rocking rock shaft 29 and causing the staplers to operate once to drive a row of staples across the blank. After the last staple-controlling block 31 operates to cause its stapling operation, the pin 76 on said block will move pawl 72 out of engagement with extension 73 of arm 61, and spring 62 will rock arm 61 and shaft 57 thus throwing pins 52 and 53 into engagement with openings 56 in the hub of sprocket wheel 49 and causing chain 32 to move at a high rate of speed until pin 64 on the first staple-controlling block 31 engages bell-crank lever 65 and moves the shaft 57 into neutral position. The pattern of blocks 31 will then remain at rest until again moved with the next box blank, the materials for which have been placed on conveyer chains 2 while the preceding blank was being wired.

The illustrative machine is set up to make the blank shown in Fig. 8, said blank having five staples in each of the two narrow sections and six staples in each of the two wider sections. Twenty-two staple-controlling blocks 31 are therefore set on the chain 32 as shown. In Fig. 8 the chain 32 has been extended in a straight line adjacent the blank to illustrate the relationship of the blocks 31 to the staples in the blank.

Figs. 10 and 11 illustrate how the pattern of staple-controlling blocks 31 may be reduced to half the number of staples desired in a box blank. The first and third sections of the blank are identical in size and have the same number of staples. Likewise the second and fourth sections are identical in size and have the same number of staples. Thus the same number of staples in like location are driven in each half of the blank and a pattern of controlling blocks 31 for

one-half of the blank may be used for both, it being only necessary to provide the middle spacer block 1 of the blank with a pin 70 and to so regulate the length of chain

5 32 that there will not be too great a space between the first and last staple-controlling blocks 31.

Obviously, the present invention is not limited to the particular embodiment shown 10 and described, but may be variously embodied, and the particular construction shown may be variously modified, as will appear to those skilled in the art. Furthermore, it is not indispensable that all the 15 features of the invention be used conjointly, since they may be used to advantage in various different combinations and sub-combinations.

Having described the invention, what is 20 claimed is:

1. A machine for use in making boxes comprising, in combination, work-forwarding means having devices for positioning a plurality of units of box parts; fastener-setting mechanism operable to drive fasteners into moving box parts; and means to control the location of fasteners at predetermined points in the work comprising a pattern of controlling members for a single unit of work operable automatically to control the location of fasteners in a succession of units of work.

2. A machine for use in making boxes comprising, in combination, work-forwarding means having devices for positioning a plurality of units of box parts; fastener-setting mechanism operable to drive fasteners into moving box parts; and means to control the location of fasteners at predetermined points in the work comprising a pattern of controlling members for a single unit of work operable automatically to effect a like location of fasteners in a succession of units of work.

3. A machine for use in making boxes comprising, in combination, work-forwarding means having devices for positioning a plurality of units of box parts; fastener-setting mechanism operable to drive fasteners into moving box parts; and means to control the location of fasteners at predetermined points in the work comprising a pattern of controlling members for a single unit of work operable automatically to effect a like location of fasteners in a succession of variably spaced units of work.

4. A machine for use in making boxes comprising, in combination, work-feeding means having positioning devices for a plurality of units of work; fastener-setting mechanism operable to drive fasteners into moving work; and means to control the number and location of fasteners driven into the work comprising a pattern of controlling members operating to control the num-

ber and location of fasteners in a single unit of work and adapted automatically to repeat its operation on each of a succession of units of work.

5. A machine for use in making boxes comprising, in combination, work-feeding means having positioning devices for a plurality of units of work; fastener-setting mechanism operable to drive fasteners into moving work; and means to control the number and location of the fasteners comprising a pattern of members operating to control the operations of the fastener-setting mechanism to locate fasteners in a single unit of work and adapted automatically to repeat its operation on each of a succession of units of work.

6. A machine for use in making boxes comprising, in combination, work-feeding means having positioning devices for a plurality of units of work; fastener-setting mechanism operable to drive fasteners into the moving work; and means to control the location of fasteners in the work comprising a pattern of selectively spaced controlling members operating to position fasteners in a single unit of work distances apart relatively equal to the spacing of said members and adapted to repeat its operation to effect a like location of fasteners in each of a succession of units of work.

7. A machine for use in making boxes comprising, in combination, work-feeding means having positioning devices for a plurality of units of work; fastener-setting mechanism operable to drive fasteners into the moving work; and means to control the number and location of the fasteners comprising a series of controlling members equal in number to the number of fasteners desired in a unit of work operating to locate fasteners in each of a succession of units of work.

8. A machine for use in making boxes comprising, in combination, work-feeding means having positioning devices for a plurality of units of work; fastener-setting mechanism operable to drive fasteners into the moving work; and means to control the number and location of the fasteners comprising an endless series of controlling members equal in number to the number of fasteners desired in a unit of work operating uninterruptedly to locate fasteners in each of a succession of units of work.

9. A machine for use in making boxes comprising, in combination, work-feeding means having positioning devices for a plurality of units of work; fastener-setting mechanism operable to drive fasteners into the moving work; and means to control the number and location of the fasteners comprising a series of selectively spaced controlling members equal in number to the number of fasteners desired in a unit of work

operating to locate fasteners in each of a succession of units of work in accordance with the spacing of said members.

10. A machine for use in making boxes comprising, in combination, fastener-setting mechanism; work-forwarding means having devices for positioning a plurality of units of box parts; and means controlling the operations of the fastener-setting mechanism to control the location of fasteners in the work comprising a pattern of controlling members for a single unit of work operable automatically to control the location of fasteners in a succession of units of work.

15. 11. A machine for use in making boxes comprising, in combination, fastener-setting mechanism; means to position a plurality of units of box parts; means to cause relative progression between said mechanism and the box parts; and means controlling the operations of the fastener-setting mechanism to control the location of fasteners in the work comprising a pattern of controlling members for a single unit of work operable automatically to control the location of fasteners in a succession of units of work.

20. 12. A machine for use in making boxes comprising, in combination, means to position and feed a plurality of units of box parts; fastener-setting mechanism operable to drive fasteners into the moving box parts; and means to controllably locate fasteners in the work comprising a pattern 25 of controlling members to locate fasteners in a single unit of work and operable without interruption to control the location of fasteners in a succession of units of work.

25. 13. A machine for use in making boxes comprising, in combination, endless work-forwarding means having positioning devices for a plurality of units of box parts; fastener-setting mechanism operable to drive fasteners into the moving box parts; and means controlling the operations of the fastener-setting mechanism to controllably locate fasteners in the box parts comprising a series of controlling members operating to locate fasteners in a single unit of box parts and adapted to repeat its operation and locate fasteners in a succession of units of box parts without stopping the machine.

30. 14. A machine for use in making boxes comprising, in combination, fastener-setting mechanism; means to feed a succession of units of work continuously to said mechanism; and means to control the location of fasteners in the work comprising a pattern of controlling members for a single unit of work operable to locate fasteners in each of a succession of units of work without interrupting the feed of the work.

35. 15. A machine for use in making boxes comprising endless chains having devices for positioning and feeding a plurality of

box blanks; means to advance said chains continuously at approximately a uniform speed; fastener-setting mechanism normally inactive during the passage of the work thereunder and adapted when thrown into operation to drive fasteners into the moving work; and means to cause operations of said fastener-setting mechanism at selected times to drive fasteners into the work at predetermined selected points comprising an endless chain having a series of selectively spaced controlling blocks secured thereto to controllably locate the fasteners in a single box blank in accordance with the location and spacing of said blocks, and means to cause said blocks to similarly locate fasteners in a succession of box blanks.

40. 16. A machine for use in making boxes comprising, in combination, endless work-forwarding means having devices to position a plurality of work-assemblies whereby an endless succession of work-assemblies may be forwarded through the machine; fastener-setting mechanism normally inactive during the passage of the work thereunder and constructed and arranged to be thrown into operation at selected times to drive fasteners into the work at predetermined points; and means controlling the fastener-setting mechanism to cause a definite number of fasteners to be driven into the work at definite points comprising a pattern of members to control the number and location of fasteners in a work-assembly and adapted to repeat its operation upon a succession of work-assemblies.

45. 17. A machine for use in making boxes comprising, in combination, means to position and feed a succession of units of box parts; fastener-setting mechanism operable to drive fasteners into the moving work; and means to cause a like number of fasteners to be driven into each of a succession of units of work in like relative positions comprising a pattern of controlling members for a unit of work, and means automatically to relate said pattern to each succeeding unit of work regardless of irregularity in the spaces between units.

50. 18. A machine for use in making boxes comprising, in combination, means to position and feed a succession of box-assemblies; fastener-setting mechanism operable to drive fasteners into the moving work; and means to control the number and location of the fasteners comprising an endless series of controlling members to locate fasteners in a work-assembly and means automatically to relate said series to each succeeding work-assembly to similarly locate fasteners in each assembly.

55. 19. A machine for use in making boxes comprising, in combination, means to position and feed a succession of box-assemblies; fastener-setting mechanism operable

to drive fasteners at intervals into the moving work; and means to control the number and location of the fasteners comprising a series of controlling members for a work-
5 assembly, means to move said members with the work-assembly, and means automatically to relate said members with each succeeding work-assembly whereby said series of controlling members for a single work-assembly
10 will operate to cause a like location of fasteners in a succession of work-assemblies.

20. A machine for use in making boxes comprising, in combination, means to position and feed a succession of units of box parts; fastener-setting mechanism operable to drive fasteners into the moving box parts; and means to control the number and
15 location of the fasteners comprising an endless series of controlling members to locate fasteners in a single unit of work, means to move said controlling members synchronously with a unit of work while they are controlling the location of fasteners therein,
20 and means to move said controlling members at a faster speed to relate them to the next succeeding unit of work.

21. A machine for use in making boxes comprising, in combination, endless work-forwarding means of a length in excess of the length of a plurality of units of work; fastener-setting mechanism operable to drive fasteners into moving work; and means to controllably locate fasteners in the
30 work comprising an endless chain only slightly longer than the length of a single unit of work, a pattern of fastener-controlling blocks carried thereby, means to relate said pattern to each successive unit of work,
35 and means to move said pattern with each successive unit of work.

22. A machine for use in making boxes comprising, in combination, fastener-setting mechanism normally inactive during the passage of the work thereunder; means having devices to position and feed a plurality of units of work; and means to cause operations of said mechanism at selected times to drive fasteners where desired in the work
45 comprising a pattern of controlling members for a single unit of work operable to control the location of fasteners in a succession of units of work.

23. A machine for use in making wire-bound boxes comprising, in combination, work-forwarding means having devices for positioning a plurality of units of box parts; binding-wire-applying means including staple-forming and driving mechanism operable to form staples and drive them over binding wire into moving box parts; and means to control the location of staples
55 in the work comprising a pattern of controlling members for a single unit of work
60 operable automatically to control the lo-

cation of staples in a succession of units of work.

24. A machine for use in making wire-bound boxes comprising, in combination, work-feeding means having positioning devices for a plurality of units of work; binding-wire-applying means including staple-forming and driving mechanism operable to form staples and drive them over binding wire into the moving work; and means to control the number and location of the staples comprising a pattern of members operating to control the operations of the staple-forming and driving mechanism to locate staples in a single unit of work and adapted automatically to repeat its operation on each of a succession of units of work.

25. A machine for use in making wire-bound boxes comprising, in combination, work-feeding means having positioning devices for a plurality of units of work; binding-wire-applying means including staple-forming and driving mechanism operable to form staples and drive them over binding wire into the moving work; and means to control the location of staples in the work comprising a pattern of selectively spaced controlling members operating to position staples in a single unit of work distances apart relatively equal to the spacing of said members and adapted to repeat its operation to effect a like location of staples in each of a succession of units of work.

26. A machine for use in making wire-bound boxes comprising, in combination, work-feeding means having positioning devices for a plurality of units of work; binding-wire-applying means including staple-forming and driving mechanism operable to form staples and drive them over binding wire into the moving work; and means to control the number and location of the staples comprising a series of selectively spaced controlling members equal in number to the number of staples desired in a unit of work operating to locate staples in each of a succession of units of work in accordance with the spacing of said members.

27. A machine for use in making wire-bound boxes comprising, in combination, binding-wire-applying means including staple-forming and driving mechanism; work-forwarding means having devices for positioning a plurality of units of box parts; and means controlling the operations of the staple-forming and driving mechanism to control the location of staples in the work comprising a pattern of controlling members for a single unit of work operable automatically to control the location of staples in a succession of units of work.

28. In a machine for use in making wire-bound boxes comprising, in combination, binding-wire-applying means including sta-

- ple-forming and driving mechanism; means to position a plurality of units of box parts; means to cause relative progression between the binding-wire-applying means and the box parts; and means controlling the operations of the staple-forming and driving mechanism to control the location of staples in the work comprising a pattern of controlling members for a single unit of work operable automatically to control the location of staples in a succession of units of work.
29. A machine for use in making wire-bound boxes comprising, in combination, binding-wire-applying means including staple-forming and driving mechanism; means to feed a succession of units of work continuously to said mechanism; and means to control the location of staples in the work comprising a pattern of controlling members for a single unit of work operable to locate staples in each of a succession of units of work without interrupting the feed of the work.
30. A machine for use in making wire-bound boxes comprising, in combination, means to position and feed a succession of units of box parts; binding-wire-applying means including staple-forming and driving mechanism operable to form staples and drive them into the moving work; and means to cause a like number of staples to be driven into each of a succession of units of work in like relative positions comprising a pattern of controlling members for a unit of work and means automatically to relate said pattern to each succeeding unit of work regardless of irregularity in the spaces between units.
31. A machine for use in making wire-bound boxes comprising, in combination, binding-wire-applying means including staple-forming and driving mechanism normally inactive while the work is passing beneath said mechanism; means having devices to position and feed a plurality of units of work; and means to cause operations of said mechanism at selected times to drive staples where desired in the work comprising a pattern of controlling members for a single unit of work operable to control the location of staples in a succession of units of work.
32. A machine for use in making boxes comprising, in combination, work-forwarding means having positioning devices for a plurality of units of box parts; fastener-setting mechanism operable to drive fasteners into moving box parts; and means to position fasteners in the work regular or irregular distances apart which latter distances need not be some multiple of a regular distance comprising a pattern of fastener-controlling members for a unit of work operable to position fasteners in a succession of units of work.
33. A machine for use in making wire-bound boxes comprising, in combination, work-forwarding means having positioning devices for a plurality of units of box parts; binding-wire-applying means including stapling mechanism operable to drive staples over binding wire into moving box parts; and means to position the staples in the work regular or irregular distances apart which latter distances need not be some multiple of a regular distance comprising a pattern of staple-controlling members for a unit of work operable to position staples in a succession of units of work.
34. A machine for use in making boxes comprising, in combination, work-forwarding means having positioning devices for a plurality of units of box parts; fastener-setting mechanism to drive fasteners into the box parts; and means controlling the operations of the fastener-setting mechanism to position fasteners in the work regular or irregular distances apart which latter distances need not be some multiple of a regular distance comprising a pattern of fastener-controlling members for a unit of work operable to position fasteners in a succession of units of work.
35. A machine for use in making wire-bound boxes comprising, in combination, work-forwarding means having positioning devices for a plurality of units of box parts; binding-wire-applying means including stapling mechanism to staple binding wire to the box parts; and means controlling the operations of the stapling mechanism to position staples in the work regular or irregular distances apart which latter distances need not be some multiple of a regular distance comprising a pattern of staple-controlling members for a unit of work operable to position staples in a succession of units of work.

In testimony whereof, I have signed my name to this specification.

ALBERT K. SMITH.
